(57) **CLAIM**

The ornamental design for a glove, as shown.

DESCRIPTION

FIG. 1 is a dorsal side plan view of a glove showing my design;

FIG. 2 is a perspective view from the dorsal side of the glove thereof; and,

FIG. 3 is a palmar side plan view of the glove thereof.
The broken line showing of a portion of the glove is for
illustrative purposes only and forms no part of the claimed
design.
